RADIANT

Charles V. Blayney, Chicago, Ill., assignor to General Combustion Company, Chicago, Ill., a co-partnership comprising Charles V. Blayney and Byron A. McAnsh

Application February 21, 1938, Serial No. 191,667

12 Claims.

(Cl. 158—7)

My invention relates to combustion and includes among its objects and advantages an improvement in the generation and application of heat to such a heat receiving instrumentality as the bottom of a tea kettle or cooking utensil.

In the accompanying drawings:

Figure 1 is a plan view and Figure 2 a side elevation of a gas burner including a radiant accor-

ding to the invention;

Figure 3 is a section on line 3—3 of Figure 1;

Figure 4 is a side elevation of the central radi-

ant core; and

Figure 5 is a detailed section of the burner on

line 5—5 of Figure 1.

In the embodiment of the invention selected for illustration, the mixer 18 is provided with the usual air inlet openings 12 with a central bridge 14 threaded to receive the gas discharge nozzle 16. The mixer has a supporting shoulder at 18 and a straight cylindrical neck 20. The burner comprises the outer annulus 22 provided with jet orifices 24 inclined outwardly and other jet orifices 26 inclined inwardly. Upon reference to Figure 1 it will be noted that the inner orifices 26 are more widely spaced than the outer orifices 24.

The annulus is part of a one piece casting including the tubular bridge 28 which is provided with a central boss 30 which fits over the neck 20 of the mixer. This joint is made snug enough to hold the burner in proper alignment, but loose enough to permit the user to lift the burner off readily. The burner casting also includes six radial arms 32 extending outward from the bottom of the annulus 22 to support the outer support ring 34. Four equally spaced lugs 36 extending upward from the outer periphery of the ring 34 provide effective socket means for holding the outer ceramic ring against lateral displacement. The outer ceramic ring is an annular body having a substantially cylindrical inside wall at 38 directly exposed to the products of combustion from the burner. The outer surface of the outer ceramic ring is serrated to provide fourteen grooves 40 separated by an equal number of buttresses 42. Near their upper ends the grooves 40 are offset inwardly as at 44 in Figure 3 so that their top openings at 46 deliver air rising through them in an upward direction inclined slightly in toward the axis of the device. The upper collar 48 encloses the upper portions of the grooves to accomplish this direction of the air rising through them. I have indicated a slit or kerf at 50 in Figures 1 and 2. Certain types of refractory of the best thermal characteristics for such work, when made up in the sizes illustrated, ex-

hibit a slight liability to crack during rapid heating or cooling, and such a kerf eliminates any danger of such cracking. The kerf is preferably formed midway of one of the buttresses 42. This avoids interfering with the action of any of the grooves, and the opening through the kerf is long and narrow so that its effects on air circulation are negligible.

Midway of the bridge 28 I provide an upwardly directed boss 52 which, in combination with the adjacent upper surface of the bridge 28 and a pair of projecting lugs 54, holds the inner radiant 56 in position. The inner radiant is provided with grooves 58 between buttresses 60 generally similar to the grooves and buttresses of the outer radiant, but on account of the smaller size of the pieces there are only seven such grooves and buttresses, and no kerf is needed. The grooves of the inner radiant face outwardly, i. e., toward the products of combustion, whereas those of the outer radiant face outwardly, but that is away from the products of combustion.

I have illustrated a metal shield comprising an upper band 62 and a lower band 64 united into a frame by risers 66, two of which have projections 68 bending under the shoulder 34 to hold the parts in place. The lower ring 64 may be made a snug fit on the lugs 36, which is the preferred construction, or one or two of the risers may be bent in above the shelf 34. The metal screen 30 performs no material function in connection with the phenomenon of combustion, but under certain conditions of service it is desirable as a mechanical protection to guard the outer radiant from mechanical injury due to blows.

The instrumentality to be heated is preferably located above the upper level of the radiants a distance equal to about half the height of the radiants in some such position as indicated by the dotted line 70 in Figure 3. At the right side of Figure 3, I have indicated four different temperatures, purely to indicate and explain the principle of action involved. Under varying conditions actual temperatures might be materially higher or lower than those indicated, but the principle would remain the same. Although the temperatures in the luminous portion of the individual flames issuing from the jets 24 and 26 would be much higher, it is assumed in the illustrative embodiment that after the processes of combustion are complete and the material issuing from the jets is also mixed with the air rising in the annular space between the radiants on either side of the annulus 22, the approximate 55

final temperature of the products of combustion will be 2000°.

By the time these gases have risen nearly to the top of the radiant, they will have delivered their sensible heat by radiation and convection to the radiants and to the cold surface at 70 and will be reduced to some such temperature as 1200°. And after they have issued from the annular space between the radiants and are lying between the 10 radiants and the surface 70, they will have been further cooled to some such temperature as 900°. Finally close against the surface 70 (which, in the case of a tea kettle would not be materially above boiling point of water) there will be a thin layer 15 of relatively cold gas lying in contact with the metal itself and delivering heat thereto. And the cooling action of the surface 70 will build up these relatively cold gases against its undersurface and they will eddy down in waves due to their greater 20 density and be wiped radially outward by the flow of the body of gases present. This indicates in a general way the temperature gradients involved in carrying heat to the surface 70 by convection.

However, the inner surface of the outer radiant 25 and the outer surface of the inner radiant both rise to temperatures of incandescence. Under ordinary conditions of service these surfaces vary from a dark cherry red to a light straw color. Accordingly the entire annular pocket above the 30 annulus and between the radiants is a source of radiation which will deliver a large amount of heat direct to the surface 70 independent of the convection action of the gases occupying the same space. On the left of Figure 3 I have drawn a 35 series of vertical arrows 72 indicating this radiation. Directly above the center of the device, on account of the low temperature of the boss 52, the effective radiation will be materially less as indicated by the shorter length of the arrows.

40 On account of the low conductivity of the material of which the radiants are made, there will be a very steep temperature drop in the wall of the outer radiant, and its outer surface, under ordinary conditions of service, never reach incandescence. But the grooves 40, the walls of which are 45 considerably above room temperature, warm the air in the grooves and direct upward currents of air as indicated by the arrows 74 at the right side of Figure 3. While these rising currents of air 50 are probably not hot enough to add appreciably to the convection of heat to the surface 70, their presence, and especially the inward inclination with which they rise to mingle with the gases rising between the radiants, enables them to 55 throttle or retard the radial flow of the gases that have come up between the radiants so that the speed of movement of these main heating gases is materially retarded. Without such retardation, the main heating gases could get up above the 60 radiants with considerably higher temperature and escape laterally from under the surface 70 with considerable higher temperature, which higher temperature would represent a direct loss of heat which is avoided by the action of the air 65 currents from the grooves 40.

Under certain conditions of operation, the coolness of the surface 70 and the temperatures of the various parts of the inner radiant 56 are such that some gases will pass downwardly as indicated by 70 the arrows at 74 in the middle of Figure 3, down along the axis of the device into the boss 52. However, this represents no loss of heat, inasmuch as these relatively warm and therefore preheated 75 gases can pass out through the weepholes 76 and mingle with the rising air around the jets 26. In

this way I avoid the formation of any pocket where explosion might take place and at the same time save the weight and undesirable heat conductivity that would result from making the boss 52 solid. The withdrawal of small amounts of recirculated gases in this way at the center, deflects the main stream of the products of combustion radially inward and further retards its escape outwardly from under the surface 70.

The inner surface of the outer ring is tapered 10 with the small end uppermost. In one successful design the ring is two inches high and its inside diameter is 4 $\frac{1}{8}$ " at the bottom and substantially $\frac{1}{4}$ " less at the top. This constriction assists in 15 retarding the movement of the products of combustion.

Without further elaboration the foregoing will so fully explain my invention that others may, by applying knowledge current at the time of application, readily adapt the same for use under various conditions of service.

I claim:

1. In a heating device, in combination: inner and outer radiants defining an annular combustion space open at top and bottom; a burner annulus in said combustion space near the bottom thereof, said annulus lying outside the lower portion of said inner radiant, and inside the lower portion of said outer radiant; passageways in said outer annulus for generating thermal convection currents and delivering them upwardly in general parallelism with the products of combustion, but inclined radially toward the center of the device; passageways in said inner radiant permitting a circulation of gases downwardly inside said radiant; a support for said inner radiant; said support having passageways through itself for the exit of the gases moving downwardly inside said inner radiant.

2. In a heating device, in combination: an annular radiant defining a combustion space open at top and bottom; a burner annulus in said combustion space near the bottom thereof; and outwardly open passageways in said radiant for generating thermal convection currents and delivering them upwardly in general parallelism with the products of combustion, whereby the lateral escape of the products of combustion is retarded.

3. In a heating device, in combination: inner and outer radiants defining an annular combustion space open at top and bottom; a burner in said combustion space near the bottom thereof; and passageways in said outer annulus for generating thermal convection currents and delivering them upwardly in general parallelism with the products of combustion, whereby the lateral escape of the products of combustion is retarded.

4. In a heating device, in combination: inner and outer radiants defining an annular combustion space open at top and bottom; a burner in said combustion space near the bottom thereof; passageways in said inner radiant permitting a vertical circulation of gases downwardly inside said radiant and upwardly outside said radiant, whereby the products of combustion are drawn radially inward above said inner radiant and their lateral escape is retarded.

5. In a heating device, in combination: inner and outer radiants defining an annular combustion space open at top and bottom; a burner in said combustion space near the bottom thereof; passageways in said outer annulus for generating thermal convection currents and delivering them upwardly in general parallelism with the prod-

ucts of combustion; and passageways in said inner radiant permitting a vertical circulation of gases downwardly inside said inner radiant and upwardly outside said inner radiant.

5. In a heating device, in combination: an annular radiant having an inwardly facing substantially cylindrical wall and an outwardly facing corrugated wall; and a collar bridging the upper portion of the corrugations in said outer wall to define closed passages directed upwardly and radially inward.

6. In a heating device, in combination: an annular radiant having an outwardly facing corrugated wall; and a collar bridging the upper portion of the corrugations in said outer wall to define closed passages directed upwardly and radially inward.

7. In a heating device, in combination: an annular radiant having an outwardly facing corrugated wall; said wall corrugations defining passages extending in a generally upward direction and of greater vertical dimensions than horizontal dimensions; and a collar bridging the upper portion of the corrugations in said outer wall to enclose the upper portions of said passages.

8. A heating device according to claim 8 in

which said radiant and collar are made up of a single piece of ceramic material.

10. In a heating device, in combination: a central metal member apertured to permit the exit of combustible gas to form a flame; a metal annulus encircling said central member and spaced outwardly therefrom to leave an annular opening surrounding and adjacent to said central member, which annular opening constitutes an entrance for secondary air; an annular non-metallic radiant resting on said metal annulus and extending above and below the center of the flame from said apertures; and spaced radial arms of metal extending outwardly from said central member below the flame to support said metal annulus.

11. A heating device according to claim 10 in which said central member, said metal annulus, and said radial arms are cast in one piece.

12. A heating device according to claim 10 in which the outer periphery of said metal annulus has means projecting upwardly adjacent the outer periphery of said radiant to confine said radiant to a position substantially coaxial with said annulus.

CHARLES V. BLAYNEY.
